VALVE CONTROLLING LEVER FOR GAS
WATER HEATERS

Leo F. Fay and Ormal Goodell, Ecorse, Mich.

Application July 13, 1932. Serial No. 622,306

1 Claim. (Cl. 137—139)

Our invention relates to a valve controlling mechanism for gas water heaters shown in the accompanying drawing and more particularly described in the following specification and 5 claim.

The purpose of this invention is to provide means whereby the supply of gas delivered to a gas water heater,—usually located in the basement of the house,—may be controlled from a 10 point remote from the heater, such as the bathroom or kitchen, without the necessity of going to the basement to light and shut off the gas. In carrying this invention into effect, a pilot 15 gas light burner is provided adjacent the burner of the heater, which is supplied with gas through a small pipe line extending from the main gas pipe line to the burner for the heater, regulated by a controlling valve, which may be used to entirely cut off the supply of gas through the 20 pilot pipe-line should the house be unoccupied or whenever desired.

The primary object of this invention is to provide a controlling valve lever adapted to be clamped upon the usual valve handle or lever 25 controlling the main flow of gas to the burner, which upon opening the valve, is ignited by the pilot light, as will be readily understood.

A further object of this invention is to provide 30 a lever controlling device simple and inexpensive in construction and operation, which may be readily removed or installed without the aid of skilled workmen, whereby the householder upon moving to a new location, may disconnect the device from the valve of the heater for installation 35 upon a valve governing the supply of gas to the heater at his new location.

A further object of this invention is to provide 40 a spring actuated controlling means which is adapted to insure against accidental opening of the gas valve when closed, or change in its adjusted position when manually opened.

A further object of the invention is to provide 45 a device which may be readily installed upon the lever arm of different types of gas controlling valves, and also for a variety of installations, dependent upon the location of the valve and heater in relation to basement walls, or fixtures.

A further object of the invention includes 50 means adapted for attachment to the gas supply pipe, irrespective of the position and direction of the latter in relation to the heater,—to receive and support a spring engaging the operating lever for returning the latter to its initial position when manually released.

55 Another feature of the invention is a nipple

threaded for installation in the gas pipe-line leading to the heater, tapped to receive the pilot-light pipe line leading to the burner.

With the foregoing and other objects in view which will appear as the description proceeds, 60 the invention further resides in the combination and arrangement of parts and in the details of construction hereinafter described and claimed, it being understood that changes may be made in the precise embodiment of the invention herein 65 disclosed without departing from the spirit of the same.

In the drawing accompanying this specification:

Figure 1 is an elevation with parts broken away 70 and in section, showing the device installed upon a gas heater, and connecting means for controlling same from a bathroom, kitchen, or at other remote location, also means for controlling the operation of same.

Figure 2 is an enlarged detail view of the 75 several parts comprising the controlling device.

Figure 3 is a perspective view of the detachable lever and overlapping plate gripping the 80 valve lever.

Figure 4 is a fragmentary view of the wall bracket for supporting the end of the operating chain or cable.

Referring now to the letters of reference placed 85 upon the drawing:

A denotes a gas water heater, B its burner, C the usual fuel supply pipe leading from a gas main to the heater.

D is a valve for controlling the supply of gas 90 from the main to the burner.

E is a valve lever of usual construction controlling the rotation or opening and closing of said valve.

F indicates a nipple adapted to be installed between the valve D, and the gas supply pipe C, 95 leading thereto. The nipple F, is tapped to receive a pilot valve G, controlling the delivery of gas through the pipe H, to the pilot light, located adjacent the burner of the water heater.

The pilot-valve G, is of usual construction and 100 is adapted for regulating, or to entirely cut off the flow of gas through the pilot pipe-line.

I denotes a detachable arm adapted to be secured to the valve lever E,—its upper end I¹ being bent at right angles that it may underlie 105 the valve lever.

J is a plate overlapping the valve lever E, perforated for the passage of bolts K, fitted with nuts, which when adjusted secure the arm I to the valve lever.

- The laterally extending portion I^1 of the arm I is provided with a plurality of slots I^a for the passage of bolts K , which when adjusted, cause the plate J and laterally extending portion I^1 of the arm to grip the valve lever, or if employed in connection with certain types of valve levers, the bolts may pass directly through slots in the lever to be secured by nuts below the arm I , thereby dispensing with the plate J .
- 10 The plate J has a depending flange J^1 which overlaps the edge of the valve lever E to secure it against slippage, that the arm I may not be accidentally disconnected from the valve lever.
- 15 I^2 denotes an aperture in the lower end of the arm I , to receive a cable or chain K^a , supported by suitable pulleys L , L suspended from a basement ceiling, whereby the cable is directed to a wall bracket M , secured to the wall of a bathroom or kitchen.
- 20 The ends of the bracket M , have outstanding slotted portions M^1 to receive the cable, to which is secured a ring N , as commonly employed by like devices for controlling the draft damper of furnaces.
- 25 Detachably secured to the gas pipe leading to the burner is an arm P fitted with an overlapping plate P^1 , secured thereto by bolts, which upon adjusting the respective elements, grip the pipe. The lower end of the arm P has a series of apertures P^2 spaced apart to receive the end of a spring S , which in turn at its opposite end is engaged to the arm I through the aperture I^2 .
- 30 Having indicated the several parts by reference letters, the construction and operation of the device will be readily understood.
- 35 The pilot light located adjacent the burner B , supplies the means by which the gas flowing from the burner B may be ignited, the flow of gas to the pilot-light through the pipe H being controlled or cut off by the pilot valve G , as required.
- 40 Upon raising the ring N attached to the cable K^a , from the position shown in Figure 1, to the upper outstanding portion M^1 of the wall bracket, the arm I^1 is raised against the action of the spring S , thereby opening the valve D for the delivery of gas from the main to the burner;—the spring serving to hold the chain rigid against accidental release of the valve.
- 45 50 When sufficient hot water has been obtained and it is desired to cut off the supply of gas to the burner, the chain is manually released that

the valve may return to its normal closed position—shown in Figure 1—through the urge of the spring S , thereby cutting off further supply of gas to the burner.

It will be noted that this device may be readily installed without the necessity of calling in the services of a gas fitter or plumber, and that it may be as readily removed to be again installed in another location by the householder without material cost or labor and without disturbing or altering the gas pipe connections already in the premises. It is therefore especially adapted for removal from one location to another should the owner so desire.

We also desire to further stress the fact that this device is especially adapted for attachment to the operating levers of various types of gas valves and may be readily connected in different locations where the general layout and arrangement of the piping varies to a very considerable extent.

Having thus described our invention, what we claim is:

In a gas valve controlling means for water heaters, a detachable arm having a laterally projecting flange perforated for the passage of bolts, whereby the arm may be clamped upon a gas controlling valve lever of a water heater; a plate adapted to overlap the gas controlling lever, also perforated for the passage of bolts, said plate having a downwardly directed flange overlapping the edge of the gas valve lever, to secure the detachable arm against lateral slippage; a plurality of bolts extending through the overlapping plate and flange of the arm, whereby the arm may be securely and detachably clamped upon the gas controlling valve lever; a spring engaged at one end to the detachable arm; a bracket arm adapted to be detachably clamped to a pipe or the like, having a plurality of apertures near its projecting end to receive the opposite end of the spring, whereby the latter may be adjustably connected thereto; a cable connected with an end of the arm detachably clamped to the valve lever, whereby the arm may be raised to open the valve against the urge of the spring; and means for supporting said cable, whereby the valve may be maintained in its adjusted position until manually released.

LEO F. FAY.
ORMAL GOODELL.
